UNITED STATES PATENT OFFICE.

FREDERICK HENKE, OF PHILADELPHIA, PENNSYLVANIA, ASSIGNOR, BY MESNE ASSIGNMENTS, TO A. H. FOX GUN COMPANY, OF PHILADELPHIA, PENNSYLVANIA, A CORPORATION OF PENNSYLVANIA.

TOY GUN.

Application filed September 21, 1926. Serial No. 136,766.

This invention relates to toy guns and more particularly to relatively small light guns in which the propulsion of the projectile is effected by the release of a spring

5 actuated piston or plunger within the shell inserted into the gun at the breech.

One object of this invention is to make a toy gun, small in size, but simulating in almost exact detail, the outward appearance 10 and the manner of manipulating a real shot gun, so that the toy gun is substantially a model of a real gun but in miniature.

A further object of the invention is to construct a toy gun which may be broken for 15 the insertion and withdrawal of cartridges at the breech thereof in almost exact duplication of the manner of operating a real gun and to fire or project from it at a mark or target with accuracy, harmless projectiles.

20 A further object of the invention is to construct and provide a toy gun which is harmless in the hands of children but will be of assistance to them later in using and handling real fire arms.

25 A further object of the invention is to make of sheet metal, in the simplest manner, and with the fewest mechanical operations of dieing, pressing and shaping, a gunlock frame, which in gun making is usually machined out of solid metal, and to make such 30 a sheet metal frame strong and rigid with respect to the stock and barrels.

A further object of the invention is to 35 make the barrels of the gun of a single piece of sheet metal so constructed that a light ball may be projected through it at high speed without any retardation or impedance due to the trapping and rarification of the air behind the projectile.

40 A further object of the invention is to make the gunlock at a minimum cost but of strong, permanent construction with few parts and without departing or detracting from the form and appearance of a real well-designed shot gun.

45 A further object of the invention is to 50 make the gunlock frame of three pieces of sheet metal so shaped, interlocked and secured together as to produce a very stiff and strong structure presenting the outward appearance of the frame of a real shotgun.

55 Other objects of the invention will appear in the specification and claims below.

In the drawings forming a part of this

specification and in which the same reference characters are employed throughout the various views to designate the same parts,

Fig. 1 is a side elevational view of the improved toy gun.

Fig. 2 is a larger view of the gunlock, a portion of the barrels, the fore-end and a portion of the stock on a larger scale than that employed in Fig. 1, parts of the same being shown in longitudinal cross-section.

Fig. 3 is a view of the same character as that constituting Fig. 2 but with certain parts sectioned to show the gunlock mechanism.

Fig. 4 is a transverse cross-section on the line 4—4 of Fig. 2.

Fig. 5 is a fragmentary view, partly in horizontal cross-section through the firing pins showing the breech lock, the breech block and the water table.

Fig. 6 is a transverse cross-sectional view through the barrels at 6, 6 of Fig. 1 but on a larger scale than that employed in Fig. 1.

Fig. 7 is a longitudinal sectional view through a loaded shell suitable for use in this improved toy gun.

Fig. 8 is a plan view of the three pieces of sheet metal united together to form the gunlock frame.

Fig. 9 is a side elevational view of the same.

Fig. 10 is a front end view of the same; and

Fig. 11 is a rear end view of the same.

The principal parts of the improved toy gun are made to present the form and outward appearance of a real firearm and, therefore, comprise the stock 1, the gunlock frame 2, the fore-end 3, barrels 4, 4', the triggers 5, 6 and the trigger guard 7. The shell loader 8 formed by a rearward extension of the trigger guard 7 somewhat simulates in form and appearance the shell ejector of a breechloader shotgun; the loader 8 may be omitted, however, if desired.

The stock 1 is of wood. The gunlock frame 2 is composed of three pieces of shaped sheet metal, namely, the main lower part 9, the upper part 10 and the intermediate interlocking part 11, the latter forming in one piece the breechblock 12 and the water table 13. Within this frame are housed all the parts of the gunlock, to be referred to

in detail below, including the breechlock 14. On the top of the frame is the breechlock release lever 15 shaped, arranged and disposed to swing horizontally as it ordinarily is in a real shotgun.

The main or lower portion or part 9 of the gunlock frame 2 is made of a single piece of sheet metal, of substantially U-shape in transverse cross-section, but the forward part is wider and shallower than the rear part. The rear part is shaped to substantially fit around the lower half of the small end of the stock 1 and the forward shallower and wider part fits under and against the rear end of the barrels 4, 4' when the parts are assembled, with the barrels 4, 4' substantially lying on the water table 13, mounted therein. At the extreme forward ends of the main lower portion 9 are alined holes 16' for the reception of a pivot pin 16 upon which is pivotally mounted the rear end of the fore-end 3. The pin 16 may be made of two parts, one threaded into the other.

The top or upper part 10 of the gunlock frame 2 is also made of a single piece of sheet metal. In the main, this piece is also substantially U-shape in transverse cross-section, but inverted and the two lower marginal edges 10' are offset toward each other so as to fit within and against the upper edges of the lower part 9 and to present a smooth outer surface to the frame when the parts are joined together. The forward end of the upper part 10 is expanded into substantially the shape of two semi-circles connected by a web to register with the rear ends of the barrels 4, 4' with which they almost abut. The rear end of the part 10 fits around the upper half of the forward end of the stock 1, which is preferably provided with depressions 1' into which the edges 10' fit.

The third and intermediate interlocking portion 11 is also composed of a single piece of sheet metal. The water table portion 13 thereof is flat and snugly fits between and just below the upper vertical edges of the forward portion of the main or lower part 9 of the frame. At the rear end of the water table 13, the sheet is bent sharply at right angles and is shaped to fit and interlock within the double circular forward end of the portion 10 of the frame 2 to form the breechblock 12 which is provided with bushings 17, 18 through which respectively extend the firing pins 19 and 20.

The forward end 21 of the interlocking member 11 is bent downwardly sharply at right angles to the water table 13, is shaped to fit within the channel of the forward part of the portion 9 of the gunlock frame, and is provided with an integral rivet 22 which passes through the opening 22' in the bottom of the part or member 9 and is headed over

on the underside of said member 9. Although it may be desirable to spotweld at x , x , the overlapping flanges of the portions 9 and 10 respectively when the parts are assembled, it may not be absolutely necessary so to do for the said flanges are provided with alined openings 23 and when the parts are assembled on the stock a pin 24 passing therethrough and through the small end of the stock holds the two parts 9 and 10 firmly together and to the stock, and the interlocking of the breechblock 12 within the forward end of the member or portion 9 holds the forward end of the portion 9 firmly with relation to the part 10 when the forward end 21 has been riveted with the rivet 22 to the main or lower part 9 as above described. The forward portion 21 forms a wall which encloses the front end of the frame immediately behind the pivot pin 16 to form a chamber in which the breech-lock 14 is housed.

Through the upturned sides of the main or lower part 9 of the gunlock frame are alined holes 25 through which a pivot pin 26 may be inserted to provide a pivot on which the triggers 5 and 6 are mounted. Below the holes 25, in the bottom of the portion or part 9, are two slots 27 and 28 through which the triggers 5 and 6 respectively pass. These triggers 5 and 6 are loosely mounted on the pin 26, but after the pin 26 has been inserted through the triggers which are restrained from movement longitudinally of the pin by the slots 27 and 28, the pin 26 may be pinched or flattened to form a projection 29 between the triggers 5 and 6 so that it may not thereafter be withdrawn. These triggers 5 and 6 are also stamped out of sheet metal and are shaped so that the lower parts thereof loosely fit and swing within the slots 27 and 28 respectively and the upper parts 5', 6' are offset transversely away from each other so as to enter and fit respectively within the slots 30 and 31 in the heads 32, 33 on the rear ends of the firing pins 19 and 20 respectively. Between the head 32 and the breechblock 12 around the firing pin 19 is a coiled spring 34 operative to normally hold the firing pin 19 on its rearmost position and the trigger 5 against the forward end of the slot 27. Between the head 33 and the breechblock 12 around the firing pin 20 is a similar spring 35, the tension of which is to hold the firing pin 20 in its retracted rear position and the trigger 6 against the forward end of its slot 28. So it is that the lower parts of the triggers 5, 6 are prevented from movement longitudinally of the pin 26 by the slots 27 and 28 and their upper ends are also held from such movement by reason of their engagement with the slots 30 and 31 respectively in the rear heads 32, 33 of the firing pins 19 and 20.

The barrels 4, 4' are formed of a single sheet of sheet metal shaped to form preferably the two cylindrical barrels 4, 4' connected together by a web 36 slightly below the tops of the barrels and forming the sight channel 37 between the adjacent barrels. The inner edges 38, 38 of this sheet are preferably spaced from the web 36 and is clearly shown in Fig. 6 to provide a clear passage 39 between the two barrels throughout their full length and adjacent these free inner edges 38, 38 the barrels are soldered or welded to a rod or wire 40 lying therebetween to close the underside of the two barrels and to hold them in rigid substantially cylindrical form.

To the underside of the two barrels 4, 4' is secured the fore-end 3 which is also made of sheet metal and is preferably of substantially channel shape tapering and becoming more shallow at its forward end and having the upper edges thereof resting tight against the undersides of the barrels 4, 4'. It is preferably secured to a rod or plate 41 soldered or brazed below the edges 38 of the sheet forming the barrels 4, 4' near the rear end of the barrels, by screws 42, 43 which may pass through bushings 44, 45 between the rod 41 and the bottom wall of the fore-end 3. In this manner the barrels are securely mounted on and carried by the fore-end 3 which in turn is pivotally connected to the forward end of the piece or member 9 by the pivot pin 16.

At the rear end of the barrels 4, 4', and firmly riveted to the rod 41 between them is a yoke or staple-like structure 46 forming a part of the breechblock 14 and adapted to pass through a slot 46' in the water table 13 when the breech in the gun is closed. Co-operating with this yoke 46 is the latch 47 in the chamber beneath the water table 13, said latch projecting downwardly from and being carried by the forward end of an arm or lever 48 which is held flat against the under-side of the water table 13 by a strap 49 secured to the under-side of the water table 13 but spaced therefrom to provide a guideway 50 between the under-side of the water table 13 and the upper side of the strap 49. Within this guideway the arm or lever 48 is adapted to move in a horizontal plane or parallel to the bottom of the water table 13. The rear end of this arm or lever 48 is provided with a keyed opening through which loosely passes a substantially vertical rod 51 having stamped therein a fin or key 52 which fits into a keyway of the arm 48. This vertical rod 51 is reduced in diameter at its lower end, is stepped into a hole 53 through the bottom of the stamping 9 of the gunlock frame, and its lower end 51' is expanded to rotatably retain in it the frame. Its upper end passes directly through an opening 53' in the upper wall of

the portion 10 of the gunlock frame. Outside of and above the gunlock frame the end of the rod or pin 51 is preferably straddle-milled to provide two flat surfaces 51" on opposite sides thereof. This upper end of the pin then passes through a similarly shaped elongated hole in the end of the breechlock releasing lever 15 and is then riveted over at its upper end 51' as clearly appears in Figs. 2 and 3.

Thus it is that the arm or lever 48 is retained in its position with respect to the water table 13 by the strap 49, although the pin 51 passes freely therethrough, except as for the keyed connection provided by the fin 52. No exact machine work is required to provide a thoroughly dependable connection between the pin 51 and the pivoted end of the arm or lever 48.

Below the strap 49, the arm or lever 48 is provided with a downwardly extending projection 54 and the opposite end of the strap 49 is provided with a similarly downwardly extending projection 55 between which is stretched a spring 56 tending to draw the latch 47 to the left (see Fig. 4) and into the loop of the yoke 46. To release the barrels and open the breechlock releasing lever 15 is pressed to the left (see Fig. 4) whereupon the latch 47 moves to the right against the tension of the spring 56 and moves out of the loop of the yoke 46 whereupon the barrel falls on the pivot pin 16 to the position shown in Fig. 3 in dotted lines. After the shells or cartridges have been withdrawn and replaced with fresh loaded ones, the breech may be closed in the ordinary manner and when the bottom of the yoke 46 passes beyond the projecting toe 47' of the latch 47, the breech will be held locked.

The forward end of the trigger guard 7 is preferably bent to form a forwardly extending tongue which when inserted through a suitable opening in the bottom of the gunlock frame may be firmly retained in position around the triggers 5 and 6 when the rear end is secured to the stock as by a screw 57.

Although the pin 24 may be sufficient to retain the gunlock frame 2 therein, a more rigid and certain connection is provided by inserting additional screws 58 and 59 through the gunlock frame into the upper and lower front end portion of the stock 1.

In order that the nature and purpose of the gun structure, above described, may be fully understood, a cartridge, as disclosed in my copending application Serial No. 138,606 and exemplified in Fig. 7, arranged and adapted to be used in this toy gun will now be described.

This cartridge consists of a metallic tube or cylinder 61 of uniform diameter outside and inside except at the discharge end 62

which is substantially reduced in diameter to provide a clean annular shoulder 63 and a forwardly outwardly tapering tip 64. The largest diameter of the tapering bore of the tip 64 is substantially the same or slightly larger than the diameter of the spherical projectile 65 and when a spherical ball is inserted into the tip 64 of the shell 60 it will be quite firmly retained there by the friction 10 between it and the slightly tapering walls of the bore of the tip 64. It may here be stated that the ball 65 is preferably of light soft wood, and having no sharp projection, and being light in weight, it may be projected 15 quite rapidly without danger of serious injury to one who might be hit with the projectile in its flight from the gun.

In making the parts of the shell, the groove 66 is not formed through the cylindrical wall thereof until the parts are being assembled and, therefore, for the present the cylinder 61 will be considered as of uniform diameter and bore except as forwardly beyond the shoulder 63 above described.

The cartridge head 67 is generally speaking a hollow cylindrical member having a circular flange 68 on one end thereof a little larger in diameter than the outside diameter 30 of the cylinder or tube 61.

The circular bore 69 of the cartridge head 67 is of uniform diameter from the forward end thereof inwardly to a point near the flange 68 where a square shoulder 70 is provided and from said shoulder 70 to the rear end or flange 68 thereof a smaller cylindrical hole 71 or bore coaxial with the bore 69 is provided.

The forward cylindrical end of the cartridge head 67 is provided with two diametrically disposed longitudinally extending slots 72, 72 disposed parallel to the axis of the cartridge head 67 and extending transversely through the said cylindrical cartridge head, and at right angles to the plane of the slots 72, 72, and near the forward end thereof is a cylindrical pin 73. The outer cylindrical surface of the cartridge head 67 is provided with a circumferential groove 74 spaced forwardly from the flange 68. On the pin 73 is pivotally mounted a latch 75 having a forwardly extending arm 76 terminating in a tooth or detent 77 and a sharp tip 78. Said latch 75 is also provided with a somewhat shorter downwardly extending arm 79 normally curving outwardly to a point close to the inner wall of the bore 69 of the cartridge head.

The latch 75 is preferably made of flat 60 sheet metal and at the intermediate portion 81, through which the pivot pin 73 passes, the latch is nearly as wide as the outside diameter of the cartridge head 67 extending into and loosely fitting within the slots 72, 72.

Within the head 67 and fitting in the cylindrical axially arranged holes or bores 69 and 71, is a push button 82 capable of slight longitudinal movement therein, the smaller rearwardly extending end terminating substantially flush with the outer rear surface of the flange 68. This push button 82 simulates in appearance the percussion cap on the end of a cartridge for real firearms.

This push button 82 is provided with a smooth conical axially disposed recess 83, the walls of which converge toward the smaller end of the said button 22, the larger diameter at the forward end thereof being not quite as large as the inner diameter of the coil spring 84 to provide a seat 85 for the rear end of said spring 84. The outside diameter of the spring 84 is such as to fit smoothly within the bore 69 and its forward end presses against the rear edges 86, 86 of the wide portion 81 of the latch 75. The spring 84 may be a light spring for its purpose is merely to normally hold the push button 82 in its rearmost position yieldingly pressed against the shoulder 70.

Also within the cylinder 61 is the hollow plunger 87, generally cylindrical in shape to freely slide within the cylinder 61, but provided at its forward end with a preferably dome-like projection 88 around which is a narrow shoulder 89 and at the center of which is a axial hole or passage 90 communicating with the chamber 91 within the plunger 87. The rear wall 92 is disposed at right angles to the axis of the plunger and is also provided with an axial hole 93 of a size to permit of the passage therethrough of the pointed end 78 and tooth or detent 77 of the latch 75.

Normally held pressed against the forward slotted end of the cartridge head 67 is a washer 94 forming a seat for the rear end of a coiled propulsion spring 95 at all times under compressive tension between the forward end of the cartridge head 67 and the rear wall 92 of the plunger 87.

It might be well to here state that the cartridge parts are assembled by first inserting the plunger 87 through the rear cylindrical end of the tube 61, then inserting the coiled propulsion spring 95 and then the washer 94.

The cartridge head assembly is made by first inserting the push button 82 into the head 67, then the spring 84, then inserting the latch 75 with the edges of the flat portion 81 in the slots 72, 72 and then inserting the pivot pin 73.

The cartridge head assembly is then inserted into the smooth cylindrical end of the tube 61 and held there against the tension of the propulsion spring 95 until the so assembled shell is rigidly secured together by forcing the metal of the cylindrical tube 61 down into the groove 74 of the head 67, thus 130

forming the groove 66 on the outside of the shell.

It should also now be made plain that when after assembly the plunger 87 is

- 5 pushed rearwardly by a short ramrod or by the loader 8 inserted through the open end 62 of the shell to the position shown in Fig. 7, so that the tooth or detent 77 catches on the inner face of the wall 92 through the 10 hole 93. The edge 96 of the wide portion 81 of the latch 75 will be substantially flush in its slot 72 with the forward end of the head 67 and against the washer 94, but the edge 97 may be slightly cut away rearwardly 15 from the forward edge of the head 67 so that the latch may be turned by said spring 95 to bring its forward end firmly against the wall of the hole 93 or to hold it in a position to re-engage the plunger when the plunger is 20 moved from the position shown in dotted lines in Fig. 7 to that shown in full lines.

- It should be also here noted that with the parts so assembled and arranged the rounded end 80 of the rearwardly extending arm 25 79 lies close to the wall of the bore 69 of the head 67 and against the forward marginal surface of conical hole or recess 83 of the push button 82, the detent 77 and the rounded end 80 being on opposite sides of the detent 75 and on diametrically opposite sides 30 of the pivot pin 73 so that when the push button 82 is pressed inwardly the tapering surface of the conical hole 83 forces the releasing arm 79 toward the axis of the cartridge 61 and also moves the detent 77 towards the said axis against the tension of 35 the spring 95 pressing on the shoulder or edge 96 through the washer 94 and when the detent 77 clears the inner surface of the wall 40 92 the plunger 87 is released and is impelled forwardly at a high speed by the stiff propulsion spring 95 until the shoulder 89 of the plunger 87 engages the shoulder 63 at the forward end or discharge end of the shell. 45 in the position shown in dotted lines in Fig. 7.

- But before the engagement of the said shoulders 89 and 63 the projection 88 will strike a sharp blow against the wooden 50 spherical projectile 65 placed in the tapered end of the tip 64 and project it, at a high speed, out of the shell.

- Having now described the main features 55 of construction, the way in which the gun is operated to project a bullet or ball will next be described.

- The cartridge 60 is first loaded, preferably by forcing the plunger 87 rearwardly within the shell by using the loader 8 until the tooth or detent 77 catches against the rear wall 92 of the plunger 87, whereupon 60 the plunger will be retained in retracted position against the compressed propulsion spring 95. A light wooden projectile 65, 65 preferably spherical, is preferably pressed

into the open end of the tip 64 of the cartridge where it remains frictionally held in the slightly tapered bore of the tip 64. The shell is now loaded.

The gun is then broken at the breech by 70 pressing the breechlock releasing lever 15 to the right, that is to say, in an anticlockwise direction with respect to the vertical shaft or rod 51, forming the pivotal support therefor and this movement of the breechlock 75 releasing lever withdraws the toe or latch 47 from the yoke 46, whereupon the barrels 4, 4' and the fore-end 3 will swing on the pivot pin 16 to the position shown in dotted lines in Fig. 3. It should here be noted that the rear end of the fore-end 3 is provided with a surface 98 concentric with the pivot pin 16 which just clears the forward free edge 100 of the main lower member 9 of the gunlock frame 2 and provides an indented shoulder 99 in the rear of the fore-end 3, forming a stop which limits the downward swinging movement of the free ends of the barrels 4, 4'. The forward edge 100 of the member 9 and the shoulder 99 in the fore-end form abutting stops to limit the downwardly movement of the free end of the barrels 4, 4' when released by breaking the gun at the breech. Two loaded cartridges 80 100 may then be inserted into the breech end of the barrels. The flange 68 thereof abutting squarely against the rear ends or edges of the barrels 4, 4'. The breech is then closed, just as it is closed in a real shotgun, by forcing the rear end of the barrels down against the water table 13, the yoke 46 of the breechlock passing through the slot 46' of the water table 13 and pressing against the outward tapered end 47' of the latch 47 of the breechlock lever or arm 48, retracts it until the said yoke passes beyond said sharp toe, whereupon the spring 56 draws the toe 47' into the opening or loop of the yoke 46 rigidly holding the rear end of the barrels down firmly against the top of the water table 13. The gun is now loaded and ready for firing.

To fire the same, the gun is aimed in the usual manner and one or both of the triggers 5, 6 are drawn rearwardly. The upper end of the trigger so withdrawn presses against the rear end of the firing pin and the firing pin (32 or 33 depending upon which trigger is pressed) slowly moves forwardly and engages the small end of the push button 82 forcing it into the cartridge. The forward movement of the push button 82 finally so depresses the latch releasing lever or arm 79 that the tooth or detent 77 releases the hollow plunger 87 which flies, forward propelled by the propulsion spring 95, and strikes the ball or projectile 65 a sharp blow which propels it through the barrel (4 or 4') and out of the barrel with considerable 115 120 125 130 velocity.

The projectile 65 is not substantially propelled through or expelled from the barrel by compressed air between the projectile 65 and the forward end of the plunger 87, but 5 rather by the impact of the plunger 87 against the projectile, the holes 89 and 93 in the plunger permitting of substantially the free passage of air through the plunger as the plunger moves rapidly toward the 10 projectile. Nor is the speed of the ball 65 impeded in its passage through the barrel, after it leaves the cartridge 60, by reason of the rarefaction of any air within the barrel to the rear of the projectile for the 15 open slot or clear space 39 forming a passage between both barrels for the full length of the barrels permits of the continuous equalization of pressure on both sides of the projectile as it travels through the barrel. 20 The pressure of the air ahead of the projectile in its passage through the barrel is no greater than it is through the air after it leaves the barrel. Little speed is lost, therefore, by the projectile in its travel 25 through the barrel, and due to the slot or passage 39, the barrel may be made sufficiently long to direct the flight of the projectile after it leaves the gun.

As soon as the pressure of the firing pin 30 on the end of the push button 82 is relieved, the coiled spring 84 returns the push button to the position with its outer end flush with the outer surface of the flange 68 as shown in Fig. 7, and the pressure of the coiled 35 propulsion spring 95 pressing against the edge 96 of the wide portion 81 of the latch 75 turns the latch 75 on its pivot 73 and the tooth 77 away from the axis of the shell or cartridge 60 moving the tooth or detent 77 40 into a position wherein the sharp or pointed end 78 of the lever is in substantial alignment with and will enter the hole 93 in the back of the plunger 87 when it is next forced rearwardly to load the cartridge, and the wall of the hole 93 hitting against the tapered end of the latch 75 will lift the tooth or detent 77 as the plunger moves rearwardly until it snaps over the rear wall 92 of the plunger to retain it in loaded position. 45 The coiled spring 84 is thus operative to normally hold the push button 82 in its outermost position; and the propulsion spring 95, in addition to supplying the power for driving the plunger 87 forwardly, 50 normally holds the forwardly extending arm 76 of the latch 75 in a position to enter the axial hole 93 in the projectile and to bring the tooth or detent into engagement with the surface of the inner rear wall of the plunger 87. 55

Thus it will be seen that the cartridge in outward appearance presents the appearance of the cartridge of a real firearm. The 60 toy gun is broken at the breech by a breech releasing lever, as it is in a real firearm.

The forward end of the barrels when released swing downwardly to open the gun at the breech exactly as in a real gun. The cartridges are inserted in the barrels at the breech as they are inserted in a real gun, 70 and the breech is closed in the same manner as in a real firearm, to wit, by merely pressing the rear end of the barrels down into alignment with the firing pins. The gun is strong and has no complicated parts to get 75 out of order. It is, therefore, durable, strong and should withstand rough usage for a long time. The light wooden bullets or projectiles fly rather rapidly, but their mass or weight is small. The gun may be discharged and the bullet projected against the hand placed close to the muzzle without causing substantial discomfort. The impact of the bullet is not enough to break a pane of glass, nor mar the finished surface of 80 furniture.

It is also to be noted that the gun is a hammerless gun. The firing-pins are not struck a blow to discharge the cartridge. The firing-pins move slowly with the triggers and at a speed corresponding to that of the triggers, and operate to merely release the plunger in the cartridge. For this reason, among others, the construction of the cartridge has been fully described herein, for 90 the gun may not be adapted for use with every kind or type of cartridge. Because, however, other cartridges may be successfully used in the gun, the cartridge is made the subject matter of and is claimed in a 95 separate application, executed by me on the same date as that of this application.

Having thus described my invention, what I claim, and desire to protect by Letters Patent of the United States is:

1. In a toy gun the combination of a hollow gun-lock frame formed by a plurality of pieces of sheet metal rigidly secured together, and having a trigger-slot therethrough, and a gun-lock mechanism mounted therein, and comprising a pivot-pin passing transversely through said frame, a trigger mounted to turn freely on said pin and passing through said slot, said slot forming a guide to position said trigger on said pin and a stop to limit the forward movement of the lower end of said trigger, one of said pieces forming the breech-block, a firing pin extending through said breech-block and having transverse slots in the rear end thereof in which the upper end of said trigger is seated, and a spring under tension to normally hold said firing-pin in its retracted position, and the lower end of said trigger in its most forward position against said stop. 110

2. In a toy gun the combination of a hollow gun-lock frame formed by a plurality of pieces of sheet metal rigidly secured together, and having two parallel trigger slots therethrough and a gunlock mechanism 115

mounted therein, and comprising a pivot pin passing transversely through said frame and two triggers mounted to turn freely on said pivot pin and passing respectively through 5 said slots, each slot forming a guide to position its trigger on said pin and a stop to limit the forward movement of the lower ends of said triggers, the said pin being provided with a projection between said triggers to prevent the withdrawal of said pin from said frame.

3. In a toy gun the combination of a hollow gun-lock frame formed of a plurality of pieces of sheet metal rigidly secured together 15 and having two parallel trigger slots therethrough, and a gunlock mechanism mounted in said frame and comprising a pivot pin passing transversely through said frame and two triggers mounted to turn freely on said 20 pin and passing through said slots respectively, each slot forming a guide to position its trigger on said pin and a stop to limit the forward movement of the lower end of the trigger therein, said pin being flattened and 25 widened between said trigger to prevent withdrawal of said pin from said triggers and frame.

4. In a double barrelled toy gun the combination of a gunlock frame of sheet metal, a 30 gunlock mechanism mounted therein, a fore-end of sheet metal pivoted to said frame and two barrels connected by a web and made of a single sheet of metal, the edges of the sheet metal of which said barrels are made being 35 between the barrels and below and spaced from said web to form a longitudinal passage between said barrels for substantially the full length of said barrels, and a rod between said barrels and below said passage, 40 rigidly secured to said barrels.

5. In a toy gun the combination of a hollow gunlock frame formed of three pieces of sheet metal rigidly secured together and comprising a top part a lower and an intermediate part rigidly locking said two other parts together and forming in the frame a water table, breech block and a breech lock chamber below the water table, a gun-lock mechanism mounted in said frame, and a breech lock mechanism mounted in said frame comprising a substantially vertical shaft journaled in said frame, a breech lock lever slidable longitudinally of said shaft but splined thereto to rotate therewith and extending under and against said water table, a support on the under side of said table and forming with the table a guide way within which said lever may oscillate with said shaft and preventing movement 50 of said lever longitudinally of said shaft, a breech latch on the forward free end of said lever, and a spring to normally hold said lever in breech locking position.

6. In a toy breech loading gun, a gunlock frame made of pieces of shaped sheet metal

and comprising a lower member substantially channel shaped in transverse cross section and having a longitudinal slot for the passage therethrough of a trigger, an upper member, also substantially channel-shaped 70 in transverse cross-section but inverted with respect to said lower member, the marginal edges of one member being offset inwardly slightly a distance equal to the thickness of the sheet metal of which they are made, to fit flat against the marginal edges of the other member and present, when so assembled, a plain substantially uninterrupted outer surface, the contacting margins of said members being rigidly secured together. 75

7. In a toy gun the combination of a gunlock frame and a stock, said frame comprising a lower member substantially channel-shaped in transverse cross section and having a longitudinal slot with a passage therethrough of a trigger and with aligned transverse holes at the forward end thereof for the pivotal attachment thereto of a fore-end, and an upper member also substantially channel-shaped in transverse cross-section 85 but inverted with respect to said lower member, the marginal edges of one member being offset inwardly slightly a distance equal to the thickness of the sheet metal of which said pieces are made, to fit flat against the marginal edges of the other member and to present when so assembled a plain substantially uninterrupted outer surface, and to provide a vertically oblong opening at the rear end of said frame within which may be 90 tightly fitted the forward end of said stock, said members being rigidly secured together. 95

8. In a toy breech loading gun, a gunlock frame made of three pieces of shaped sheet metal and comprising a lower member substantially channel-shaped in transverse cross-section and having a longitudinal slot for the passage therethrough of a trigger, an upper member also substantially channel-shaped in transverse cross-section but inverted with respect to said lower member, the marginal edges of one of said members being off-set inwardly slightly to fit flat against the marginal edges of the other member, and to present when so assembled, a plain substantially uninterrupted outer surface, said members being rigidly secured together, and a third or intermediate member forming a breech block and water table fitting and interlocking within the forward end of said upper member and rigidly secured to said lower member. 100 105 110 115 120

9. In a toy breech loading gun, a gunlock frame made of pieces of shaped sheet metal and comprising a lower member substantially channel-shaped in transverse cross-section and having a longitudinal slot for the passage therethrough of a trigger, an upper member, also substantially channel-shaped in transverse cross-section but in- 125 130

verted with respect to said lower member, the marginal edges of one member being offset inwardly slightly a distance equal to the thickness of the sheet metal of which they are made, to fit flat against the marginal edges of the other member, so that the sides of said frame will present when assembled, a plain substantially uninterrupted outer surface, the contacting margins of said members being rigidly secured together, the forward end of said upper member forming the frame end of the breech and having its marginal edge shaped to conform to the rear end of the barrel and the forward end of said lower member extending forwardly to fit against the outer surface of the rear end of the barrel.

10. In a toy gun, the combination with a gunlock frame made of sheet metal and including a breechblock made of sheet metal and a trigger mounted within said gunlock frame, a firing pin slidably mounted in said breech block, a spring for yieldingly holding said firing pin in its rearmost position and the lower end of said trigger cooperating therewith in its forward position the rear end of said firing pin provided with a transverse slot and the upper end of said trigger slidably fitting within said slot.

20. 11. In a toy gun, the combination with a gunlock frame made of sheet metal and including a breech block made of sheet metal and a trigger mounted within said gunlock frame, a firing pin slidably mounted in said breech block, a spring for yieldingly holding said firing pin in its rearmost position and the lower end of said trigger cooperating therewith in its forward position the rear end of said firing pin provided with a transverse slot and the upper end of said trigger slidably fitting within said slot, a barrel pivotally connected to said frame to form a breech between the rear end of said barrel and said frame, a cartridge comprising a spring-pressed plunger, a latch for holding said plunger in its retracted position and a longitudinally movable plunger releasing member in the rear end of said cartridge, said cartridge being adapted to fit within the breech of said gun, whereby when said trigger is manually pressed rearwardly, the firing pin moves forwardly against said latch releasing member to release said plunger from said latch.

30. 12. In a breech loading toy gun, the combination of a gunlock frame providing a water table provided with a slot therethrough, a barrel pivotally mounted on the forward end of said frame to form a breech between the rear end of said barrel and said frame, a yoke rigidly secured to said barrel and passing through said slot when said

breech is closed, a substantially vertical rod mounted in said frame, a breech locking releasing lever above and outside of said frame and rigidly mounted on the upper end of said rod, a breech lock lever mounted on said rod to rotate therewith, a strap on the under side of said water table frame and spaced therefrom to form a guide within which said lever is free to swing and to provide limits to the swing of said lever in either direction, a latch on the free end of said breech lock lever and a spring normally yieldingly holding said latch within said yoke and said barrel rigidly against said water table when said breech is unbroken.

13. In a toy breech lock loading shot gun the combination of a frame, a gun lock mechanism mounted in said frame, a fore-end pivotally mounted on said frame to break and close the breech of the gun, the forward end of said frame being of a shallow channel shape in transverse cross section and the forward edge thereof being concaved rearwardly, and the rear end of said fore-end being fitted within the forward end of said frame and indented to form an abutment which fits against the forward concave edge of said frame when said breech is broken.

14. In a toy breech loading gun, using shells in which the impelling of the projectile is effected by a spring pressed plunger within the shell, retained, when operative to discharge a projectile, remote from the open end of the shell, by a releasable detent within the shell, the combination of a trigger guard, means to secure said trigger guard to the gun, and a loader comprising a stiff rigid finger extending from one end of said trigger guard, offset from the gun from the point of its attachment to the gun, and of a length a little greater than the travel of the plunger in the shell, whereby the plunger may be forced into engagement with said detent by manually forcing said shell longitudinally over said finger.

15. In a toy breech-loading gun using a shell which is loaded by compressing a spring down into the shell into locking engagement with a detent within the shell, the combination of a trigger-guard and a shell loader formed as a stiff rigid finger, extending from one end of said trigger-guard, and offset from and extending generally in the direction of the adjacent gun structure, and of a length sufficient to compress said spring to its "loaded" position by manually forcing said shell longitudinally over said finger.

In witness whereof I have hereunto set my hand this 13th day of Sept., 1926.

FREDERICK HENKE
